UNITED STATES PATENT OFFICE

2,628,421

CAN OPENER

James H. Crews, San Marcos, Tex., assignor to
The First National Bank of San Marcos

Application October 24, 1949, Serial No. 123,269

1 Claim. (Cl. 30—6.1)

1

This invention relates to a can opener.

An object of the invention is to provide a can opener which is provided with a blade for cutting a discharge opening in the top of the can and is also provided with a tang or punch which will, at the same time, form an air inlet opening.

The opener has been designed for use in connection with metal cans containing liquid, such as beer cans.

It is a further object to provide an implement of the character described wherein the can support is so related to the blade and punch that the opener can be operated by a single hand of the operator.

A still further object of the invention is to provide an opener of the character described of such construction that the can will automatically swing into position clear of the blade and punch so that it can be readily removed when opened.

Other objects and advantages will be apparent from the following specification, which is illustrated by the accompanying drawings, wherein:

Figure 1 is a side elevation of the opener shown partly in section and in can receiving position.

Figure 2 is a side elevation of the opener shown in active position.

Figure 3 is a vertical, sectional view taken on the line 3—3 of Figure 2.

Figure 4 is a fragmentary, vertical, sectional view taken on the line 4—4 of Figure 2.

Figure 5 is a fragmentary, vertical sectional view taken on the line 5—5 of Figure 3, and

Figure 6 is a cross-sectional view taken on the line 6—6 of Figure 1.

Referring now more particularly to the drawings, the numeral 1 designates an upright stand having a widened base 2 for the support of the implement.

The numeral 3 designates a forwardly curved bracket, one end of which is provided with a vertical, elongated anchor 4 and whose other end has a slot 5 in its lower side. The anchor 4 conforms in shape to, and is countersunk into, the upper end of the stand with its outer sides and top flush with the corresponding parts of the stand. This anchor may be removably secured to the stand by any suitable means, such as the screws 6.

Intermediate its ends the bracket has the de-

2

pending side lugs or extensions 7, 7 and the upper end of the hanger 8 is pivotally connected with said lugs on a horizontal axis and is rearwardly turned at approximately a right angle to the main body of the hanger.

The lower end of the hanger carries a circular platform 9 having an upstanding, annular, marginal rim 10 within which the can, when mounted on the platform, fits.

Between the lugs 7 and countersunk into the lower side of the bracket 3 there is a blade shank 11 which may be secured to the bracket in any approved manner and whose forward end is forwardly and downwardly curved, having the side edges 12, 12 and terminating in the point 13.

Seated in the slot 5 and pinned or otherwise secured therein there is a shank 14, whose forward end is downwardly turned and formed with a shoulder 15 and a depending tang or punch 16.

The hanger, being shaped as above explained and with the weight of the platform 9 thereon, will normally hang in rearward position, as shown in Figure 3, so that the can may be inserted thereon and will clear the blade 11, as shown in Figure 1.

When the can is located on the platform the can and hanger may be grasped and pulled forwardly so as to move the top of the can into contact with said blade and punch and a discharge opening and an air inlet opening will be formed in said top. The forward movement of the can will be stopped by the shoulder 15.

Upon release of the hanger, the can will swing into position clear of the blade, as shown in Figure 1, and may be readily removed.

If desired, the base 2 may be securely fastened to a suitable support on which it is mounted, for convenience in operating the opener.

Should it be desired to do so, the anchor 4 may be disconnected from the stand 1 and fastened to a wall or other permanent, upright structure by means of the screws 6, or by any other suitable securing means, and the opener then used as a convenient kitchen implement for opening metal cans of any kind which contain liquid.

The drawings and descriptions are illustrative merely, while the broad principle of the invention will be defined by the appended claim.

What I claim is:

50 A can opener comprising, a stand, a bracket extending forwardly from the stand and whose

free end is provided with a slot, lugs spaced apart and depending from the bracket a hanger whose upper end is rearwardly turned at substantially right angles and pivoted between the lugs and depending therefrom, a platform secured to the lower end of the hanger and extending forwardly therefrom to receive a can, a shank secured in said slot formed with a shoulder and a depending punch beneath the shoulder and a blade whose shank is countersunk into the under side of the bracket between said lugs and whose forward end is downwardly curved and formed with cutting side edges and terminating in a point, said hanger being movable forwardly

and positioned to carry the top of the can on the platform into contact with said blade and punch to perforate said top.

JAMES H. CREWS.
